UNITED STATES PATENT OFFICE.

FRANK E. GETTS, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

SWITCH.

1,212,161.

Specification of Letters Patent.

Patented Jan. 9, 1917.

Application filed October 4, 1915. Serial No. 53,873.

To all whom it may concern:

Be it known that I, FRANK E. GETTS, a citizen of the United States, residing at Chicago, in the county of Cook and State of Illinois, have invented a certain new and useful Improvement in Switches, of which the following is a full, clear, concise, and exact description, reference being had to the accompanying drawings, forming a part 10 of this specification.

The subject matter of this invention is an electrical switch.

Switches for opening and closing electrical circuits carrying large quantities of current have been subject to the general defect of employing only a part of the material in conducting currents. This is due to a number of defects of the switches as normally constructed. It has been customary in the prior art to wedge the switch blade between two spring fingers in order to form contact between the stationary terminals and the blade. The wedging has been found necessary in order to maintain the fingers in contact with the blade, but the very action of wedging drives the fingers apart so that imperfect contact is obtained. In general only a small part of the surface of the blade is held in contact with the spring fingers. This is especially difficult to overcome in larger sizes and current carrying capacities of switches.

The object of the present invention is to provide an improved form of switch structure in which a maximum of contact will be obtained between the stationary lugs and the switch blade or its blades.

I have found that it is possible to obtain a very good bearing surface of the switch blade or blades and the stationary terminals or lugs by making the blades self alining with respect to the lugs so that they are free to adjust themselves to the sides of the lugs and thus obtain a maximum of surface contact.

In the accompanying drawings which form a part of the present specification, I have shown a number of switch structures embodying my invention.

Figure 1 is a side elevational view of a switch constructed in accordance with my invention; Fig. 2 is a front elevation of the same; Fig. 3 is a side elevation of a modification; and Fig. 4 is an enlarged detail view 55 of the switch shown in Figs. 1 and 2, and

Fig. 5 is a fragmentary elevation of a modification.

The movable part of the switch comprises a pair of blades 1 and 2 which are clamped at one end to a stationary lug 3 by means of a bolt 4 and a pair of spring washers 5 and 6 which maintain a uniform spring pressure upon the blades 1 and 2 to hold them against the sides of the lug 3. The lug 3 is secured to a suitable base board or panel 60 7 which may be of slate, marble or the like as is usual in switch-board construction. The switch blades 1 and 2 which are pivoted on the bolt 4 are held together at their outer ends by means of a bolt 8 and spring washers 9 and 10 similar to the spring washers 5 and 6. A suitable handle 11 is provided with an extension or tongue 12 which serves as a spacer for the extreme outer ends of the switch blades 1 and 2. 75 This tongue 12 serves as a spacer and prevents the blades from being drawn too closely together by the bolt 8 and the spring washers 9 and 10. A pair of pins 13 and 14 is secured to the tongue 12 and serves to 80 connect the handle 11 with the switch blades 1 and 2. It is to be particularly noted, however, that these pins are not riveted or otherwise secured to the blades 1 and 2 but are passed through holes which are slightly 85 larger than the pins to allow of a free sidewise movement of the ends of the blades 1 and 2 with respect to the tongue 12. It can be seen thus that the blades are not rigidly secured to the handle 11 so far as sidewise 90 movement of the blades is concerned, but for the purpose of rotating the blades about the bolt 4 the handle serves as a rigid extension of the blades 1 and 2.

A suitable lug 15 is secured to the base-board 7 in such position as to be engaged by the blades 1 and 2. The lug 15 has an open slot 16 cut therein to receive the bolt 8 when the switch is moved to the closed position with respect to the lug 15. The outer 95 end of the lug 15 may be suitably beveled to give a finished appearance and to assist the blades in alining themselves when the switch is closed. Where the switch is to serve for reversing connections another lug 100 17 may be provided for coöperation with the blades 1 and 2. The lug 17 is spaced from the lug 3 in the same manner as the lug 15 and is also provided with a notch or open slot 18 for receiving the bolt 8. The 105

spring washers 5, 6, 9 and 10, which I have shown as being employed for holding the switch blades against the terminals, are made of spring material. These washers are formed in a cup or conical shape and are provided with saw-cuts or kerfs 19 in order to provide a number of spring arms for holding the blades in proper position. It is to be understood that this is merely one form in which the blades may be yieldingly pressed together and I am aware that a great variety of spring means may be employed for the same purpose. The particular spring means is not of the essence of my invention.

It can be seen that normally when the switch blades 1 and 2 are out of engagement with the outer lugs 15 and 17 that the spring washers 9 and 10 and the bolt 8 will hold the outer ends of the blades 1 and 2 against the tongue 12. This tongue serves as a spacing block for holding the ends of the blades 1 and 2 from coming too close together. When the switch is thrown to the closed position the blades 1 and 2 are free to spread at their outer ends and to adjust themselves to the terminal 15 so as to gain a maximum area of contact. The inner or pivot ends of the blades 1 and 2 are similarly free to adapt themselves to the surface of the lug 3. The attachment of the handle 11 is such as to allow free sidewise or lateral movement of the blades 1 and 2 so that they are practically free to adjust themselves to all the inaccuracies of the switch terminals.

In Fig. 3 I have illustrated a modification in which instead of employing a single bolt 8 and spring washers 9 and 10 for holding the switch blades 1 and 2 against the outer terminal 15, I employ a pair of bolts 20 and 21 with co-operating spring washers on each side of the lug 22 which does not have the slot 16. The lower terminal lug 23 is similarly formed and is aligned with the lugs 3 and 22 so that the switch blades may be moved to connect with it. The switch blades 1 and 2 may be made relatively thin in order that they may have freedom to adjust themselves to the sides of the connected lugs.

Fig. 5 illustrates the end of an open air switch. Instead of employing a handle for operating the switch an eyelet 25 is provided. The eyelet 25 is provided with shoulders 26 for spacing the blades apart the proper distance. Otherwise the switch is constructed as shown in Fig. 1 or 3, as desired. The switch is operated by inserting a hook in the eyelet 25.

While I have shown a particular embodiment of my invention, I do not intend to be limited to the details of construction shown or described but intend that all such modifications and variations as will suggest themselves to one skilled in the art and coming

within the spirit of my invention be included within the terms of the following claims.

What I claim is:

1. In combination a pair of stationary switch terminals, a pair of separate moving switch blades, spring means at a plurality of points on said switch blades for pressing said blades against said terminals, and spacing means secured to said switch blades, said spacing means allowing free lateral movement of said blades between the outer ends thereof.

2. In combination a pair of stationary switch terminals, a pair of separate switch blades movable into engagement with both of said terminals, a spacing block between said blades, said block being of less width than the width of said terminal, and spring means operating independently of said spacing block to hold said blades firmly in engagement with the sides of both of said terminals, said blades having operating means secured thereto for moving said switch blades.

3. In combination a stationary terminal, a pair of switch blades pivoted on said terminal, spring means for pressing each of said blades against the sides of said terminal, a second terminal, a spacing block between the outer ends of said switch blades, means for retaining said spacing block between said blades, said means allowing free lateral movement of said blades and spring means for pressing said blades against said spacing block, said block being of less width than the adjacent terminal.

4. In combination a pair of stationary switch terminals of substantially the same thickness, a pair of separate substantially parallel switch blades pivoted on opposite sides of one of said terminals, spring means for pressing said blades against said one terminal, spring means operating independently of said first spring means for pressing said blades against the sides of said second terminal, and means for moving said switch blades in unison, said means comprising spacing means between said parallel switch blades, the outer ends of said blades being laterally movable with respect to each other.

5. In combination a pair of switch terminals of substantially the same thickness, a pair of separate substantially parallel switch blades pivoted on one of said terminals, spring means for holding said blades against said one terminal, spring means independent of said first spring means for holding said blades against the sides of said second terminal, a spacing block between the ends of said blades and means for retaining said spacing block in position between said blades, said means projecting from the sides of said spacing block, the outer ends of the blades engaged by said spacing block being laterally movable with respect to each other.

6. In combination a pair of stationary terminals of substantially the same thickness, a pair of separate movable switch blades, said blades being pivoted on one of 5 said terminals, spring means for holding said blades against the sides of said terminal, spring means independent of said first spring means for holding said blades against the sides of said second terminal, a spacing 10 block between the ends of said blades, pins secured to said spacing means and passing loosely through the sides of said blades.

7. In combination a pair of stationary terminals of substantially the same thickness, a pair of switch blades pivoted upon 15 one of said terminals, spring means for pressing said blades against said one terminal, independent spring means for pressing said blades against said other terminal, a 20 spacing block between the ends of said blades, a pin passing through said blades and secured to said spacing block and a handle secured to said spacing block for moving said switch blades to open or closed position.

8. In combination a pair of stationary 25 switch terminals, a pair of floating blades for connecting said switch terminals, spring means for retaining said floating blades against the sides of said switch terminals, a handle for moving said blades into and out 30 of contact with said terminals and spacing means between said blades for allowing a full floating action of said blades.

9. In combination a pair of stationary switch terminals, a pair of moving switch 35 blades pivoted to one of said terminals, spring means for pressing said blades against the terminals, spacing means between said blades, said spacing means being secured to the outer ends of said blades 40 and having means projecting loosely through the switch blades to permit of limited lateral movement of the blades to adapt them to the terminals.

In witness whereof, I hereunto subscribe 45 my name this 24th day of September, A. D. 1915.

FRANK E. GETTS.

It is hereby certified that in Letters Patent No. 1,212,161, granted January 9, 1917, upon the application of Frank E. Getts, of Chicago, Illinois, for an improvement in "Switches," errors appear in the printed specification requiring correction as follows: Page 2, line 74, claim 1, after the word "blades" insert the words *between the outer ends thereof*; same page and claim, line 76, after the word "blades" insert a period and strike out all to the end of the claim; and that the said Letters Patent should be read with these corrections therein that the same may conform to the record of the case in the Patent Office.

Signed and sealed this 6th day of February, A. D., 1917.

[SEAL.]

R. F. WHITEHEAD,

Acting Commissioner of Patents.
